WALKING PUSH TOY

Edward Francis Donovan, Dayton, Ohio, assignor
to Cappel, MacDonald and Company, Dayton,
Ohio

Application March 1, 1943, Serial No. 477,617

1 Claim. (Cl. 46—149)

This invention relates to walking and push toys.

An object of this invention is to provide a toy of the walking or animated type which is so constructed that it may be entirely formed out of wood, and will be of sufficiently sturdy construction so that it will withstand rough handling by a child.

Another object of this invention is to provide a toy which is cut to the resemblance of an animal in which the legs are pivotally supported from the body, and the movement of the legs will cause the head to swing, when pushed, thereby providing an amusing toy for small children.

A further object of this invention is to provide a toy of the kind which is simple in construction so that it may be made and sold at small cost.

To the foregoing objects, and others which may hereinafter appear, the invention consists of the novel construction, combination and arrangement of parts as will be more specifically referred to and illustrated in the accompanying drawings, but it is to be understood that changes, variations, and modifications may be resorted to which fall within the scope of the invention, as claimed.

Figure 1 is a detail side elevation partly broken away of a walking toy constructed according to an embodiment of this invention.

Figure 2 is a detail top plan of the toy.

Figure 3 is a rear elevation partly broken away and in section of the device.

Figure 4 is a perspective view of the head operating bar.

Figure 5 is a fragmentary rear elevation partly in section of a modified form of this invention.

Figure 6 is a fragmentary rear elevation partly in section of another modification of this invention.

Figure 7 is a fragmentary sectional view taken on the line 7—7 of Figure 6.

Referring to the drawings and first to Figures 1, 2 and 3, the numeral 10 designates generally a body which has a configuration such as to simulate an animal or other object, and is provided with a forwardly projecting portion 11 having a recess 13 in which one end of an elongated handle 12 is adapted to be secured. The body 10 is preferably constructed out of wood, and the handle 12 is also constructed of wood and may be glued or otherwise fixedly secured in the recess 13 so that the handle 12 will project upwardly and forwardly of the body 10.

The body 10 has pivotally mounted on the opposite sides thereof a pair of leg members 14 and

15. The leg members 14 and 15 are of like construction and each includes a shank portion 16 which terminates at its upper end substantially flush with the upper portion of the body 10. The shank portion 16 is formed with a convex or arcuate forward edge portion 17, and the shank 16 merges at its lower end in a foot 18. The foot 18 is formed with a convex lower edge 19 merging with the curved or convex edge 11 of the shank 16, and the foot 18 is formed with a rearwardly projecting portion 20. The leg 14 is provided with an opening 21 through the shank portion 16, and a pivot pin 22 is extended loosely through the opening 21 and is secured as by gluing or the like in an opening 23 formed in the body 10. The pin 21 is provided at its outer end with a head 24 to limit the outward movement of the leg 14 on the pin.

A head structure 25 is pivotally mounted on the upper end of the body 10, being pivotally mounted on an upwardly projected dowel 26 which is secured as by gluing or other fastening means in a recess 27 formed in the body 10. The head 25 is formed with a downwardly opening recess 28 within which the projecting upper portion of the pivot member 26 is adapted to loosely engage. In order to provide a means whereby the head 25 may pivot about the pivot member 26, I have provided an elongated bar 29 which may be glued or otherwise fixedly secured to the head 25, the bar 29 engaging in a downwardly opening recess 30 which is cut transversely across the lower end of the head 25. The bar 29 is formed at the opposite ends thereof with V-shaped slots 31 thereby providing a pair of outwardly divergent arms 32. The head 25 is held on the body 10 by means of a pair of headed pins 34. The pins 34 have their shank portions 35 seated in openings 36 formed in the upper end 40 of the leg 14, and the head 37 of the pin 34 is disposed above the arms 32 of the cross bar 29. The cross bar 29 is formed with a central opening 38 through which the pivot member 26 loosely engages. The upper side 33 of the arms 32 are tapered downwardly and outwardly so that the heads of the pins 34 can freely rock in the V-shaped slots 31.

The toy disclosed in Figures 1, 2 and 3 is adapted to be made entirely out of wood, whereas the toy shown fragmentarily in Figure 5 is adapted to be made out of wood with a small portion of metal as will be hereinafter described. The toy shown in Figure 5 includes a body 10a similar to the body 10 which has pivotally secured thereto a pair of legs 14a and 15a. The head

25a is mounted on the upper end of the body 10a, being pivotally mounted on a metal pivot member 39 which is driven or threaded into the upper end of the body 10a. The head 25a is formed with a downwardly opening recess 28a in which the pivot member 39 loosely engages. A cross bar 40 extends through a downwardly opening recess 41 formed in the lower end of the head 25a and is formed in the opposite ends thereof with forks 42. Headed nails 43 are extended loosely through the forks 42, the heads 44 of the nails 43 engaging on the upper sides of the arms of the forks 42. The legs 14a and 15a are pivotally mounted on nails 45 which loosely engage through holes 46 formed in the shanks of the legs, and the heads 47 of the nails 45 engage the outer sides of the legs.

Referring now to Figures 6 and 7, there is disclosed a further modification of this invention including a body 10b which may be constructed according to the body 10 and which has legs 14b and 15b pivotally mounted on the opposite sides thereof. A head 25b is pivotally mounted on a nail or pivot member 39b which is secured in the upper end of the body 10b and loosely engages in an opening 28b formed in the lower end of the head 25b. The legs are pivotally mounted on nails 45b which engage through holes 46b formed in the legs, and the heads 47b engage on the outer sides of legs. The nails 45b are driven into the sides of the body 10b.

In order to provide for rocking or swinging of the head 25b on the pivot member 39b, I have provided a pair of screw eyes 48 which may be threaded into the head 25b adjacent the lower end of the head, the eyes 49 engaging loosely about a head pivot member or nail 43b. In the present instance, each screw eye is formed with the eye portion 49 thereof downwardly offset from the shank portion 50, so that only a small portion of each pivot member 43b need be disposed above the upper ends of the legs.

In the use of this toy, the handle 12 which constitutes a draft means is pushed forwardly, the legs 14 and 15 engaging on a plane surface. As the toy is pushed forwardly, one leg will contact with the ground or plane surface, the engaging leg swinging rearwardly with respect to the body 10. As the engaging leg swings rearwardly, the opposite leg, which at this time will be lifted from the surface will, under the weight

of the projecting foot portion 20, swing forwardly and will contact the plane surface when the first leg rocks rearwardly a sufficient distance to lower the body 10 to effect contact of the opposite, and at this time, forwardly disposed leg. As the legs 14 and 15 swing in alternate directions, the head operating bar 29 will be rocked on the pivot member 26. The motion of the legs is illustrated in dotted lines in Figure 1, wherein the leg 14 is in its foremost position with the rearwardly projecting portion 20 contacting the plane surface. The leg 15, at this time, is out of contact with the plane surface, but will be moved forwardly at its lower end by the weight of the rearwardly projecting foot portion, and also by forward rocking of the pivot member 29 which will not only turn the head 25 on the pivot 26, but will also forcibly swing the leg 15 forwardly to a ground or surface engaging position.

20 This toy may be painted or otherwise colored to simulate the desired animal or object and will provide a source of amusement to a child while at the same time providing a sturdy article which will withstand relatively hard usage.

25 Various toys have heretofore been provided in the prior art by which a simulated walking motion is effected but it is thought that the present toy is unique in respect to being a push type walking toy as distinguished from the pull type.

30 What is claimed is:

35 A walking toy comprising a body member, an elongated handle fixed to said member, a leg on each side of said member, means pivotally securing said legs on said member, a pivot pin fixed to the upper edge of said body member and extending upwardly therefrom, a head loosely mounted on said pivot pin, said head having a transverse slot in the lower end thereof, a transverse head 40 swinging bar fixedly secured in said slot and extending from the opposite sides of said head, said bar being formed with outwardly opening V-shaped slots in the ends thereof, and headed pins fixed in the upper ends of said legs and 45 loosely engaging in said V-shaped slots, said headed pins cooperating with said bar in effecting alternate rocking of said legs and also constituting the sole retaining means for retaining said head on said body.

50 EDWARD FRANCIS DONOVAN.
